WELL PUMP

Filed Feb. 27, 1924

FIG. 1

FIG. 2

FIG. 3

INVENTOR

Thomas J. Cotton,

UNITED STATES PATENT OFFICE.

THOMAS J. COTTON, OF BURKBURNETT, TEXAS, ASSIGNOR TO LESTER D. MOWREY, OF BURKBURNETT, TEXAS.

WELL PUMP.

Application filed February 27, 1924. Serial No. 695,494.

To all whom it may concern:

Be it known that I, THOMAS J. COTTON, a citizen of the United States, residing at Burkburnett, in the county of Wichita and State of Texas, have invented new and useful Improvements in Well Pumps; and I do declare the following to be a full, clear, and exact description of the invention, such as will enable others skilled in the art to 10 which it appertains to make and use the same.

The invention relates to well pumps and it is my principal object to provide a device that will retard the amount of sand 15 entering the valve chambers of the pump, thus increasing the life and efficiency of said valves.

A further object of the invention is to provide a liquid seal below the working barrel 20 of a well pump to prevent gas from entering the valve chambers. Great difficulty has been encountered in pumping oil wells heretofore, where they produce gas with the oil, the chief trouble being that the gas prevents the standing and traveling valves 25 from closing, thus preventing efficient pumping of the well. Attention is also directed to the fact that gas forcing oil through valves when they are partly opened, causes 30 a friction and cuts the oil, thus reducing the volatile constituents and market value thereof.

A further object of the invention is to provide a vacuum release in connection with 35 oil well pumps to prevent holding the traveling and standing valves closed.

A further object is to enable the more regular pumping of an oil well by regulating the flow of oil into the pumping chamber, and also provide fluid in the perforated 40 tubular member as hereinafter described, at all times to prevent corrosion of the perforations therein.

Yet a further object is to provide a settling chamber for sand below the pumping chamber that can be easily emptied and cleaned.

With the foregoing in view, the invention resides in the novel subject matter herein- 50 after described and claimed, the description being supplemented by the accompanying drawing forming a part of this application, wherein,

Figure 1 is a partly sectioned view.
55 Figure 2 is an elevation of Figure 1.

Figure 3 is a partly sectioned view of the perforated member and the settling chamber.

In the drawing the various parts are designated by numeral reference characters. 1 is 60 a pump working barrel of the well known design, which is threaded into the coupling 2, 3^a is a standing valve, which may be of any suitable design, the drawing, however, illustrates the well known ball valve type, 65 3 is a traveling valve, 4 is valve cups attached to the valve 3 as shown. 5 is a perforated tubular member threaded into the coupling 2. The perforations 5^a therein being more clearly illustrated in Figure 3. I 70 have found it more desirable to have sixteen holes spaced in staggered relation having four holes on each quarter of the tubular member 5, however, a greater or less number of holes may be used when desired. 6 is an 75 air hole in the side of the tubular member 5 for the purpose hereinafter set forth. 7 is a coupling threaded over the lower end of the tubular member 5, as shown. 8 is a 80 cylindrical member threaded into the lower end of the coupling 7. The lower end of said cylindrical member being closed, as shown in Figure 3. 9 is a tubular member threaded into the central portion of the coupling 7 and extending upward in the tubular member 5, the upper end thereof being spaced below the bottom of the coupling 2. 10 is a tubular member attached to the lower portion of the standing valve 3^a and 85 projecting downward a substantial distance 90 into the upper portion of the tubular member 9, the outer wall of the tubular member 10 being in spaced relation with the inner wall of the tubular member 9. It will be noted that the holes 5^a are of a greater 95 diameter than the hole 6 in the tubular member 5.

In operation, the device is lowered to the bottom of a well having tubular connection to the top of the well, the cylindrical member 8 rests on the bottom of the well and may be of various lengths to enable the spacing of the perforated member 5 any desired distance from the bottom of a well, oil comes into the tubular member 5 through 105 the perforations 5^a therein and rises above the top of the tubular member 9 and flows therein, the oil is pumped therefrom through the tubular member 10, a portion of the sand contained in the oil will settle in the 110

bottom of the tubular member 5 above the coupling 7, however, the greater portion of the sand in the oil will settle through the tubular member 9 into the cylindrical member 8 where it may be emptied when the tubing is pulled from the well. It will be noted that the oil in the tubular member 5 cannot be pumped below the level of the hole 6 therein for the reason that when the oil is lowered to the level of the hole 6, air will come in therethrough thereby releasing the vacuum in the tubular member 5, until sufficient oil has come into the said tubular member 5 to raise the level of the oil above said hole 6, thus preventing the vacuum from holding the standing and traveling valves closed. The weight of the oil in the tubular member 5 will prevent gas from entering therein and holding the said traveling and standing valves open, it will be noted that this device prevents the vacuum of a well from holding the valves closed, and also prevents the gas of a well from holding the valves open, thus providing the desired pumping conditions at all times.

It is believed from the foregoing description the nature and advantages, as well as the operation of the device, will be read-

ily apparent, however, I desire to indicate clearly in the record that I do not limit myself to the specific construction herein shown and described, and that such changes may be resorted to, when desired, as fall within the scope of what is herein claimed.

What I claim is:

In combination, a well pump including a plunger, a standing valve and a traveling valve, a tubular member attached to the lower end of said pump, having a plurality of holes intermediate its ends, a nipple attached to the lower end of said perforated tubular member having a centrally reduced threaded portion therein, a centrally disposed tubular member threaded into the reduced portion of said nipple and extending upward in the said perforated tubular member, the top thereof being spaced below the bottom of the said well pump, a small hole in the said perforated tubular member spaced below the top of the said centrally disposed tubular member so as to release the vacuum therein when the oil is lowered to that level, a cylindrical member attached to the lower end of the said coupling the lower end thereof being closed.

THOMAS J. COTTON.
